ABRAHAM GOODMAN AND JACOB GOODMAN, OF BROOKLYN, NEW YORK

BARRETTE

Application filed April 24, 1929. Serial No. 357,636.

This invention relates to improvements in hair fasteners of the barrette type.

The objects of the invention are to provide a hair fastener having a hinged tongue which is adapted to firmly grip the hair to hold it in place; to provide a hinge of novel and simple construction; and to provide a catch for the free end of the tongue, which catch covers said end when in closed position and holds it against accidental unlocking movement.

With these, and other objects in view, the invention consists in the novel construction and arrangement of parts hereinafter described, and illustrated in the accompanying drawings, in which:

Figure 1 is a longitudinal sectional view of the barrette.

Fig. 2 is a bottom plan view.

Fig. 3 is an enlarged section through the hinge on line 3—3 of Fig. 1.

Fig. 4 is an enlarged section through the hinge on line 4—4 of Fig. 3, and,

Fig. 5 is an enlarged section through the catch on line 5—5 of Fig. 1.

The device comprises a barrette bar 1 curved in the direction of length, which bar may be made of pyroxolin, metal, or any other suitable material. The bar is preferably convexo-concave in section to provide the required strength and stiffness with a minimum quantity of material, and to provide an ornamental curved front surface, although bars of other shape may be used if desired.

A metal tongue 2 is hinged to the back of the bar 1 at one end thereof. The tongue is also similarly curved in the direction of length, and is convexo-concave in section to render it rigid. One end of the tongue is bent or coiled inwardly to form a cylindrical pivot 3 about which the tongue turns freely and smoothly.

The tongue is secured to the bar by means of a hinge 4 which loosely embraces the pivot 3 and passes through a slot 5 in the tongue adjacent to the pivot. The slot 5 is somewhat wider than the width of the hinge 4 to permit of slight lateral angular movement of the tongue with respect to the hinge. The hinge may be made of the same kind of material as the bar, and it is cemented or other-

wise suitably secured thereto in fixed position.

A catch or guard 6 is fastened to the inner surface of the opposite end of the bar to engage and hold the narrowed free end 7 of the tongue in its closed position. The catch may be made of a single piece of metal bent in hook shape and preferably having two upturned side flanges 8 between which the end 7 of the tongue is received and held against accidental disengagement.

In applying the barrette to the hair, the hair is engaged in between the tongue 2 and the bar 1, and the free end of the tongue is then locked in the catch to retain the device in place in the hair, the loose play of the tongue in its hinge permitting of the necessary lateral movement of the tongue required to lock it in place.

Modifications in the details of construction and arrangement of parts herein illustrated and described may be made without departing from the scope of the invention as defined in the claims.

What we claim is:

1. A barrette comprising a bar curved in the direction of length, a rigid tongue of convexo-concave section curved lengthwise and having one end coiled inwardly to form a pivot about which it turns, a slot in the tongue adjacent the pivot, a hinge secured to one end of the bar loosely embracing the pivot and passing through the slot in the tongue, the slot being slightly wider than the width of the hinge to permit lateral play of the tongue with respect to the hinge, and a catch at the opposite end of the bar to hold the free end of the tongue in closed position.

2. A barrette comprising a bar of convexo-concave section curved in the direction of length, a rigid tongue also of convexo-concave section curved in the direction of length and having one end bent to form a pivot about which it turns, a slot in the tongue adjacent the pivot, a hinge secured to one end of the bar loosely embracing the pivot and passing through the slot in the tongue, the slot being slightly wider than the width of the hinge to permit lateral

play of the tongue with respect to the hinge, and a catch at the opposite end of the bar having upturned side flanges between which the free end of the tongue is engaged and locked when in closed position.

ABRAHAM GOODMAN.
JACOB GOODMAN.
